UNITED STATES PATENT OFFICE.

WILLIAM J. BURNS, OF DETROIT, MICHIGAN.

CAMP KIT.

1,377,391.

Specification of Letters Patent.

Patented May 10, 1921.

Application filed June 21, 1920. Serial No. 390,634.

To all whom it may concern:

Be it known that I, WILLIAM J. BURNS, a citizen of the United States of America, residing at Detroit, in the county of Wayne 5 and State of Michigan, have invented certain new and useful Improvements in Camp Kits, of which the following is a specification, reference being had therein to the accompanying drawings.

10 This invention relates to a combination box, table and bench and the primary object of my invention is to provide articles of the above nature that may be folded or distended, the folded articles providing a 15 parcel that is exceedingly compact and capable of holding other articles, and the distended articles providing useful pieces of furniture that may be used for various purposes.

20 Another object of this invention is to provide a combination box, table and stand of the above class that may be advantageously used for outdoor camping purposes, and as such conveniently carried on the running 25 board of an automobile or similar vehicle.

A further object of this invention is to provide a collapsible camping outfit wherein in a foldable box provides a container for camp stools, table legs and a lunch or cooking outfit the foldable box when collapsed serving as a table top while the lid of the box is provided with foldable supports so that it may be utilized as a bench.

A still further object of my invention is 35 to provide a combination box, table and bench, wherein the parts are constructed with a view of reducing the cost of manufacture and at the same time retain those features by which safety, durability and ease 40 of assembling are secured. With such ends in view, my invention resides in the novel construction, combination and arrangement of parts to be hereinafter specifically described and then claimed.

45 Reference will now be had to the drawings, wherein

Figure 1 is a perspective view of the table;

Fig. 2 is a similar view of a portion thereof, showing the table top by dot and dash 50 lines;

Fig. 3 is a longitudinal sectional view of the box;

Fig. 4 is a cross sectional view of the same, and

55 Fig. 5 is a perspective view of the bench.

Reference will first be had to Figs. 3 and 4 of the drawings showing an oblong box or container comprising a bottom wall 1 having hinged side walls 2 and hinged end walls 3 with a detachable lid 4 adapted to 60 close the box or container. The side walls 2 are hinged so as to be lowered into a common plane with the bottom wall 1 and said side walls have the ends thereof flanged or provided with angle bars 5 to engage the 65 vertical edges of the end walls 3 and assist in maintaining said end walls in a raised position relative to the bottom wall 1, so as to form the box or container. Coöoperating with the flanges or angle bars 5 are hold-fast devices 6 carried by the end walls 3 and adapted to engage keepers 7 carried by the 70 side walls 2.

The end walls 3 have the outer sides thereof provided with suitable handles 8 so that 75 the box can be conveniently carried and afford places for fastening devices. The inner sides of said end walls have transverse cleats 9 adjacent the upper edges thereof. The end walls 3 are hinged to the ends of the 80 bottom wall 1 in order that said end walls may be swung downwardly when the box is collapsed and used as a table top, as shown in Fig. 1, in which instance the angle bars 5, serve as end ledges to prevent lateral 85 displacement of matter placed on the table top. A type of hinge may be used for connecting the side walls 2 to the bottom wall 1 so that the table top will present a smooth and uninterrupted surface. 90

The lid 4 has depending flanges 10 to engage the outer sides of the walls 2 and 3 and assist in maintaining said walls in a set up position and this lid is adapted to serve as 95 a bench board, as shown in Fig. 5.

Hinged to the inner wall of the lid 4 adjacent the ends thereof, as at 11 are leg members 12 adapted to be maintained in diverging relation by pivoted link braces 13 connecting rounds 14 of the members 12 and 100 a cleat 15 located centrally of the lid 4. Each leg member 12 is preferably in the form of a pair of diverging legs connected by the round 14 and a transverse member 16 at the upper ends thereof and by which the leg 105 member is hinged to the lid 15. The link braces 13 have rule joints 17 of a conventional form so that said braces can be folded to swing the leg members 12 into parallelism with the lid 4, as clearly shown in Fig. 3. 110

The box is of sufficient size to receive one or more camp stools 18 of a conventional form, a lunch box 19 or other camping paraphernalia, and in addition to such articles the box accommodates a series of cross legs which are also collapsible. Each cross leg comprises a bar 20 and pivotally connected to the sides thereof, as at 21 are Z plates 22 supporting bars 23 which may be swung on 10 to the bar 20, to permit of each cross leg occupying a comparatively small space within the box.

The end cross legs are pivotally connected to the lower ends of the side cross legs, as 15 at 24, and the upper ends of the end cross legs are pivotally connected to the upper ends of the side cross legs, as at 25, thus permitting of all of the cross legs being distended to form a rigid framework on 20 which the table top may be placed. To prevent accidental collapse of the end and side cross legs and provide a table top support, one of the side cross legs, at the top and at each end thereof, has pivoted connecting 25 members 26 which are swung into interlocking engagement with the other side cross leg, as best shown in Fig. 2. With these connecting members in inactive positions at one of the cross legs all of the cross legs can be 30 collapsed so as to form a compact structure that can be readily placed within the box, as shown in Fig. 3.

From the foregoing it will be observed that I have devised a novel camping kit that may 35 be readily strapped or otherwise mounted on the running board of an automobile without occupying valuable space within the automobile, and that the contents of the kit are fully protected against dust and

the elements. The various articles to be 40 formed from the kit can be easily and, quickly set up and may be made of wood or other light and durable material with sufficient hardware to protect the parts of the 45 kit when roughly handled.

It is thought that the utility of my invention will be apparent without further description, and while in the drawings there is illustrated a preferred embodiment of my invention, it is to be understood that the structural elements are susceptible to such changes in size, shape and manner of assemblage as fall within the scope of the appended claim.

What I claim is:—

A camp kit comprising a box having a bottom wall and hinged end and side walls adapted to be placed in the same plane as the bottom wall to form a table top, angle bars carried by the ends of said side walls for bracing said end walls when in box formation and providing ledges when in table top formation, means carried by the end walls of the box to maintain all of said walls in box formation, a lid for the box adapted to coöperate with said means in maintaining the box formation, collapsible means carried by the inner wall of said lid and normally housed in the box and adapted to be distended to support said lid so that it may be utilized 70 as a bench, and legs adapted to support said box when used as a table top.

In testimony whereof I affix my signature in the presence of two witnesses.

WILLIAM J. BURNS.
